STORM WINDOW

Farley J. Wilkinson, Homewood, Ill.

Application August 31, 1946, Serial No. 694,189

8 Claims. (Cl. 160—90)

1

The present invention relates to improvements in storm windows and therewith interchangeable screens of the type which are mountable either on the regular double hung type of sash window or applicable to the outside of the frame thereof with provisions for removing and interchanging screen panels and storm window glass.

It is one of the objects of the present invention to provide a type of storm window in which the extra glass intended for the additional insulation is spaced either outwardly from the regular glass on the upper sash, inwardly from the regular glass of the lower sash, or is contained in a special frame located outside of the window itself.

A further object of the invention is to provide ready means for interchanging glass for screen panels in a manner not requiring the use of any special tools.

A further object of the invention is to provide sash which is provided with an extra pane of glass to constitute the storm window, said glass being readily attached and detached from the sash itself without the use of any special tools.

Other objects of the invention include the provision of special sliding members for the attachment and securing of the panels of the sash or the special frames provided therefor.

The invention is illustrated in two sheets of drawings accompanying the present specification, in which:

Fig. 1 is a front elevation of a window embodying the invention viewed from the outside;

Fig. 2 is a cross section through Fig. 1, along the line 2—2 thereof;

Fig. 3 is a detail perspective view of one of the parts of the construction;

Fig. 4 is a perspective view of a slide latch used to secure the parts which hold the window panes or screens;

Fig. 5 is a perspective view of a special type of metal frame used to hold glass or screen panels;

Fig. 6 is a cross sectional view along the line 6—6 of Fig. 1, on an enlarged scale, of a portion of the sash with the thereto secured panel which constitutes a storm window;

Fig. 7 is a detail fragmentary perspective view of a metal channel which is permanently attached to the sash and to which the frame carrying the storm window is secured;

Fig. 8 is a fragmentary elevational view, in exploded form, of the frame that is secured to the sash, also showing the method of constructing the corner thereof;

Fig. 9 is a perspective view, on an enlarged

2

scale, of a special connector used for making up the corner shown in Fig. 8;

Fig. 10 is a front elevational view of a window provided with an outer frame for holding alternatively either storm sash or a screen panel;

Fig. 11 is a perspective view of a special frame utilized in the construction shown in Fig. 10;

Fig. 12 is a cross sectional view, on a considerably enlarged scale, of the details of the construction shown in Fig. 10, being taken along the line 12—12 of Fig. 10;

Fig. 13 is a perspective view of a portion of the lower right hand corner of the construction shown in Figs. 10 and 11 looking from the inside of the room toward the outside;

Fig. 14 is a fragmentary perspective view of one end of a frame that is permanently attached to the outside of a window and which serves to hold the frame which holds the screen panels or the storm window glass;

Fig. 15 is a fragmentary perspective view of the frame which holds either the glass or the screen panel; and

Fig. 16 is a fragmentary perspective view, showing the details of the manner of attaching the permanent holding frame to the outer parts of a window frame.

The present invention provides a simple, inexpensive and easily applied storm window or screen which is neat in appearance and which renders either the glass or the screens readily removable without the use of screws, bolts or loose or projecting parts of any kind. It is applicable both to windows of the common casement type, as well as to double hung windows.

Referring first to that part of the invention which relates to storm windows which are slideable with double hung sash, such as illustrated in Figs. 1 through 9, there is provided in connection with each sash an extra sheet of glass constituting the storm window which sheet is held within a surrounding frame which encloses the edges of the glass on all four sides thereof. On the outside of the upper sash, and on the inside 45 of the lower sash, there are provided, respectively, rectangular frames which are capable of locking engagement with the frames that hold the extra glass, slideable means being also provided, which, in conjunction with suitable slots and projections, are capable of effectively affixing the framed extra glass on the outside of the upper sash and on the inside of the lower sash. As a result there will be obtained many of the benefits of a storm window, the dead air space between the ordinary glass of the window and the

added glass serving as an effective insulating medium against loss of heat.

In Fig. 2 which shows a window as it appears from the outside, the window will be seen consisting of a window frame 17 within which are hung the two double hung sash 18 and 19, the latter being the lower sash and the former the upper. Affixed to the outer side of the upper sash 18 is the outside storm window 20 while affixed to the inside of the lower sash 19 is the inner storm window 21. This is accomplished by surrounding a pane of glass 22 by a metallic channel frame 23. In order to insure a tight weatherproof fit between the channel frame 23 and the pane 22, suitable resilient insulating material, for example, sponge rubber 24, or some mastic composition is interposed between the frame 23 and the pane 22 (see particularly Fig. 6). Permanently affixed to the sash 19 is a channel frame 25 which is preferably nailed, for example by means of nails 26, to the sash 19 (see Fig. 6). In order to insure a weather tight fit a suitable mastic composition, for instance sponge rubber 27, substantially fills the inside of the channel frame 25, and therefore causes a part of this material to abut tightly against the sash 19.

This frame is further illustrated in Fig. 8 which also shows the manner of assembly at the corners, which is as follows: A suitable connecting member 28 (illustrated on an enlarged scale in Fig. 9) and which is provided with a number of cut out portions 29, is forced with each of its legs into the interior of channel frame 25 so as to lie between the outer and inner flanges whereafter the inner flange is deformed so as to extend into the cut out portions or recesses 29, thereby locking the connecting member 28 in place, and therefore also serving to keep the frame members tightly together at the point of juncture.

The permanent frame 25 is moreover more fully illustrated in Fig. 7 where it will be seen that it has a longitudinal depression 32 which serves to contain the heads of the nails 26. It also has a rolled or bent over edge 33 and two terminal flanges 31 and 34 which lie in the same plane and both of which abut against the sash.

The frame which holds the pane 22, consists of a sheet metal channel a portion of which is illustrated in perspective in Fig. 5 and is broadly designated by the reference numeral 23. This channel frame 23 consists of an outer flange 35 and an inner flange 36, which lie in planes substantially parallel to each other, the ends of the flanges 35 and 36, however, being obliquely bent toward each other at 37 and 38, so as to be in gripping engagement with the pane 22. Depending from the lower flange 36 is a web 39 which terminates in a further horizontally extending web 40 which leads to a further downwardly extending web 41, the sheet then being bent 180° to form a vertically extending web portion 42 which in turn leads to an obliquely extending web portion 43 which leads directly to the upper flange 35, eventuating a channel member of substantially the shape shown in Fig. 5. The rounded bottom portion 44, as can best be seen in Figs. 5 and 6, is cut away to provide a cut out portion 45 and a corresponding slot 45' while the obliquely extending web portion 43 is provided with a slot 46.

The permanent channel 25 as may best be seen in Fig. 7 is cut away to provide a slot 47. A slideable latch 48 serves to connect the frame 23 with the permanently affixed channel frame 25.

In connecting the two frames 23 and 25 use is

made of a flat metal strip 49 (Figs. 3 and 6) which is inserted into position within the member 23 by being slipped through the slot 45'. The upper edge of said strip has an upwardly extending tongue 50 which passes through and beyond slot 46 when said strip is in place. The latch 48 comprises a slideable member 51 (see Fig. 4) having an upper bead 52 and also a flange 53 at its lower edge, the latter being provided with an extension 54, which last mentioned portion forms the actual latching means. As can best be seen in Fig. 6, the flange 53 is bent rearwardly and then upwardly so as to lie in the slot or cut-out 45 and engage behind the part 41 of the channel member 23, while the extension 54 is disposed at a right angle to said flange so as to enable it to slidably engage with the portion 33 of the channel member 25 thereby holding the two channel members 23 and 25 together. The extension 54 is of such length as to permit it to pass through the slot 47. The upper bead 52 of the member 51 is bent around and slidably engages the extension 50 of member 49. Shoulders 45'' at the ends of slot 45 serve to limit the amplitude of sliding movement of latch 48.

In assembling the parts, the frame 23 has attached thereto a soft rubber gasket 55 by means of a suitable adhesive, this being secured to flange 36 of said channel member. This soft rubber gasket 55 is pressed against the outer flange 30 of the channel member 25, while the tongue 54 of the latch 48 is in such a position that it will register with and pass through the cut away or slot 47 of the channel member 25, whereafter the latch 48 is slid laterally so as to cause the tongue 54 to engage underneath the portion 33 of channel member 25, thereby locking the parts together.

It will be self evident that a plurality of these latching members 48 will be necessary, and for example, eight of them have been indicated in Fig. 1, although it is obvious that perhaps four of them will suffice, while even a larger number than eight might be used.

By reason of the fact that the soft rubber gasket 55 is tightly pressed against the upper flange 35 of channel member 23, there will be a tight fit between the two channel members, thus excluding dust, water and air. All that it is necessary to do to affix the storm window is to press the pane 22 and the surrounding channel member frame 23 against the already affixed channel member 25 with the latch members in such position that they will fit into and pass through the cut away portions 47 of the said frame member 25, and then to slide the latch members until they engage as described.

While the method of affixing the device has been described in full in connection with the sash 19 in Fig. 6, there is also shown in place the regular window glass 57 kept tight by a strip of putty 57'. It will be obvious that exactly the same arrangement is used in connection with the upper sash 18 and the window 20 except that in this case the storm window is on the outside. By reason of this construction it is possible to slide the window up and down without in any way interfering with the dead air space between the regular window glass and the extra panes 20 and 21.

The metallic parts are preferably made of some non-rusting sheet metal such as aluminum or aluminum alloy, or brass, copper, and the like.

Where screening is to be used, it is preferred

to use the construction such as illustrated in Figs. 10 through 16.

In this construction there are applied to the outside sash, frame 60 of the sash (see Fig. 11), sheet metal angular housings 61 which are provided with nail holes 62 for purposes of nailing them to the frame 60. The lower side of the housing member 61 may be provided with drain and ventilating openings 63 and 63' respectively. The lower housing member 61 is nailed to the sill 64 of the window. These members 61 thus form a box like framework or housing within the window frame 60.

Attached to the inwardly extending flanges 61' of the housing members 61 are the permanent retaining frame members 65 which perform substantially the same function as the channel frames 25 illustrated in connection with Figs. 1 through 9, except that their manner of attaching is different. An end view, partly cut away, of the retaining frame 65 is shown in Figs. 12 and 14 where it will be seen that it consists of a vertical web portion 66, and therefrom horizontally extending upper flange 67, a parallelly thereto disposed lower flange 68, the flange 68 having a downwardly extending portion 69, a horizontal portion 70 which is then bent outwardly and upwardly at 71 and 72, and finally bent rearwardly to form the flange 73.

The forward edge of the upper flange 67 has a downwardly extending portion 74, horizontally extending portion 75, another downwardly extending portion 76 and a horizontally extending terminal portion 77 which latter lies directly above and parallel to the flange portion 73 leaving, however, a slight space 78 therebetween. This space is adapted to receive the inwardly extending flange portions 61' of the housing members 61. Self tapping screws 79, or other suitable fasteners, are employed to fasten the parts 61, 77 and 78 together as shown in Fig. 12. Therefore by this construction the retaining frame 65 will be kept in place and will extend all around the window, there being two of these, one for the upper window and one for the lower window, but both bearing the same reference numeral, as they are identical in structure. They are connected together at about the center of the window by a transverse strip 80, which performs the same function relative to the flanges 73 and 77 as do the flanges 61 of the housing frame.

There will thus be present two frames 65 which may either serve to support storm window panes 22 or screens 82. These screens 82 or panes 22 are retained in metallic channel frames 23 which are identical in construction with those already described, when glass is used. However, if a screen is to be used, for instance as indicated in Figs. 10 and 12, a suitable screen fabric 82 may have at its outer periphery suitable strips 83, the screen extending into a suitably screen-retaining frame 84 which consists of a substantially closed channel into which the screen is inserted and crimped as at 85. Such types of frames are well known. The thickness of the screen frame 84 is preferably the same thickness as the window pane 22 so that frame member 23, such as already described, may be employed.

In this form of the invention, the locking of the glass pane or screen holder or frame 23 to the retaining frame 65 is made possible by forming slots 86 in portions 75 and 76 of said frame 65 through which the tongues 54 of the latch 48 may pass as best seen in Fig. 14. The portion 75

76 is slotted at 87 to allow the tongues 54 to engage under the portion 75, upon sliding of the latch member 48, thereby locking the parts together.

The frame 23 may, if desired, be fastened together at the corners in substantially the manner shown in Fig. 15 in which the vertical portion of the frame is provided with a slot 88 near the upper end thereof through which an ear 89 extends, being bent upwardly as shown in the figure, and therefore serving to hold together the mitered corners of the metallic channel frame 23.

It will be evident that if desired a pane 22 may replace the screen 82 or two screens 82 may be used, both in the upper and lower part of the window frame so that the window may be opened from either top or bottom and yet have the benefit of a screen, or the entire window may be closed with window panes 22 to serve as a storm window. Inasmuch as both the screen and the pane can be inserted from the inside of the window, there will be no necessity for going outside of the building to place either the screen or the storm window in position; and even the housing frame 61 may be applied from the inside of the building.

It will be obvious that the present construction presents many structural advantages and is also extremely convenient for use by the comparatively unskilled householder, and is particularly advantageous in that it is not necessary to use ladders or scaffolding in order to put these storm windows or screens in place, as all this can be done from within the building. The advantages in case of tall apartment buildings and the like will be immediately apparent.

The exact shape of the various parts may of course be departed from to a considerable extent provided only that the inter-relationship of the parts remains substantially as shown and will accomplish substantially the same functions.

While metal has been described as the preferred material for manufacturing the channel frames, it will be obvious that suitable plastic material may be used to replace them, and modern industry knows many such materials which are both weather-proof and have the necessary strength and resilience to operate as shown.

Thus when making the sliding latch member 48, this may be made of a suitable plastic sheet material which may, if desired, be molded into position while hot, and which will retain its shape after cooling down.

While the methods of connecting the mitered ends of the frame are convenient as shown herein, the invention is not by any means to be limited to this manner of connecting the mitered corners of the frame, as many other mechanical methods are known to effect this purpose.

Accordingly applicant claims:

1. Screen and storm window construction comprising a frame permanently attached to a window sash and a panel-supporting member carried by said frame, said member and frame being mutually secured by slidable locking means.

2. Screen and storm window construction comprising a frame permanently attached to a window sash and a panel-supporting member carried by said frame, said member and frame being mutually secured by slidable locking means carried by said supporting member.

3. In a screen and storm window construction having a frame permanently attached to a window sash and a panel-supporting member thereon to be secured, the improvement which comprises

slidable latching means carried by said member, said means comprising a latch having a straight web, a rebent portion and a transversely extending flange at the other edge thereof engageable with a portion of the said frame.

4. Screen and storm window construction comprising the combination of a window sash with metallic frame-supporting members, a hollow metallic panel-frame mounted on said members, a panel supported on said panel-frame, said panel-frame consisting of channels having opposed parallel flanges and a connecting web extending at right angles to said flanges and bent sharply back upon itself to form a guide for a sliding latch; said frame-supporting members comprising an open channel having a relatively wide connecting web and a substantially U-shaped flange extending therefrom at right angles; latching members comprising a web provided with lugs outstanding therefrom capable of sliding engagement with said U-shaped flange, said latch members being carried by said panel-frame.

5. Screen and storm window construction comprising the combination of a window frame with metallic frame-supporting members, hollow metallic panel-frames, panels supported thereby, said panel-frames consisting of channels having opposed parallel flanges and a connecting web extending at right angles to said flanges and bent sharply back upon itself to form a guide for a sliding latch; said channels being provided with longitudinal opposed slots at numerous places along their extent adjacent the juncture of the flanges and connecting web, latch-engaging plates extending through said slots and extending a short distance above one of said slots; said frame-supporting members comprising an open channel having a relatively wide connecting web and a substantially U-shaped flange extending therefrom at right angles; latching members comprising a web provided with lugs outstanding therefrom capable of sliding engagement with said U-shaped flange, said latch members being carried by said panel-frames, and being loosely curved around the extending portion of the latch-engaging plates and around the bent-back portion of the web of the panel frames.

6. Means for attaching storm window panes to a sliding sash comprising a frame-supporting member secured to said sash adjacent the periphery of a normal window pane, already installed therein, such frame-supporting member consisting of an open channel filled with an elastic material and secured to a sash with its open side

thereagainst, also being provided with a reversely bent latch-engaging flange extending longitudinally thereof; a pane-supporting frame consisting of a hollow channel having two relatively wide parallel pane-engaging flanges and a connecting web therefor, said web being provided along its extent with a number of opposed plate-receiving slots and bent back upon itself at about 180° to form latch-guiding means; latch-engaging plates extending through said slots and protruding above one of said flanges; latches, each consisting of two flanges, a straight connecting web and an outstanding lug, slidably carried by said frame; the flanges of said latches being bent around and slidably respectively on the protruding portion of said engaging plates and the latch-guiding means on the web of said pane-supporting frame, the lugs of said latches being engageable with said latch-engaging flange.

20 7. Screen and storm window construction comprising the combination of a window sash with metallic frame-supporting members, a hollow metallic panel-frame mounted on said members, a panel supported on said panel frame, said panel-frame consisting of channels having opposed parallel flanges and a connecting web extending at right angles thereto and bent sharply back upon itself to form a guide for a sliding latch; said frame-supporting members comprising a channel provided with a cut-away portion for the passage of a latch-lug; latch members slidably on said guides and comprising a web provided with a lug outstanding therefrom and extendable through said cut-away portion and slidably engageable the non-cut-away portion of said panel-frame, said latch members being carried by said panel-frames.

30 8. Means for connecting panel-carrying frames and supporting frames therefor, said frames being in the form of channels provided with latch-passing slots, which means comprise latches slidably on the panel-carrying frames and provided with lugs passing through said slots and slidably engageable with an inner surface of the said supporting frame.
